[57] CLAIM

The ornamental design for a key holder, substantially as shown and described.

DESCRIPTION

FIG. 1 is a front perspective view of a key holder showing my new design;

FIG. 2 is a side elevational view taken from the side shown in FIG. 1;

FIG. 3 is a front elevational view thereof;

FIG. 4 is a rear elevational view thereof;

FIG. 5 is a side elevational view taken from the opposite side of FIG. 2;

FIG. 6 is a top plan view thereof;

FIG. 7 is a bottom plan view thereof;

FIG. 8 is a cross-sectional view thereof taken substantially along the mid-horizontal axis showing the lower half of FIG. 2;

FIG. 9 is a cross-sectional view thereof taken substantially along the mid-vertical axis of FIG. 2;

FIG. 10 is a front perspective view of a second embodiment of the key holder embodying my new design;

FIG. 11 is a side elevational view taken from the side shown in FIG. 10;

FIG. 12 is a front elevational view thereof;

FIG. 13 is a rear elevational view thereof;

FIG. 14 is a side elevational view taken from the opposite side of FIG. 12;

FIG. 15 is a top plan view thereof;

FIG. 16 is a bottom plan view thereof;

FIG. 17 is a cross-sectional view taken substantially along the mid-horizontal axis showing the lower half of FIG. 11;

FIG. 18 is a cross-sectional view taken substantially along the mid-vertical axis of FIG. 11.
